UNITED STATES PATENT OFFICE.

ERNEST SCHMITZ, OF SAN FRANCISCO, CALIFORNIA, ASSIGNOR TO SCHMITZ DOOR OPENER COMPANY, OF SAN FRANCISCO, CALIFORNIA, A PARTNERSHIP COMPOSED OF ERNEST SCHMITZ AND HENRY L. WISSIG.

DOOR MANIPULATOR.

Application filed March 14, 1923. Serial No. 624,950.

To all whom it may concern:

Be it known that I, ERNEST SCHMITZ, a citizen of the United States, residing at the city and county of San Francisco and State of California, have invented new and useful Improvements in Door Manipulators, of which the following is a specification.

This invention relates to door opening and closing devices of the type which may be operated from a comparatively remote point, to manipulate the entrance door of a building.

It is the principal object of the present invention to generally improve and simplify devices of the character referred to, so as to provide an efficient door manipulator requiring but a minimum amount of effort for operation, and which is designed to be positive in operation and practically immune to breakage and other disorders necessitating repairs.

In carrying out this object, I provide a simply constructed mechanism which may be permanently mounted and concealed in a wall above a door and operatively connected to the latter. A device, designed for manual manipulation, for operating this mechanism is located at a desirable point, which may be remote from the door. The mechanism may be actuated by the device mentioned to unlatch the door and open and then close the door, and permit it to latch.

One form which the invention may assume is exemplified in the following description and illustrated by way of example in the accompanying drawings, in which:

Fig. 1 is a schematic view disclosing the application of the invention.

Fig. 2 is a view in plan disclosing the preferred form of my invention applied to a door.

Fig. 3 is a side elevation of the same.

Referring more particularly to the accompanying drawings, 10 indicates the entrance door of dwelling. This door is hinged to a door frame 11 which is built between vertical stud elements 12 of the wall of the building. These studs are connected above the door frame by a horizontal brace 14. Secured to this brace is a bracket bearing 15 which pivotally supports an arcuate operating arm 16. This arm is formed on an arc struck from the pivotal point 17. The

arm 16 is formed with a slotted outer end 55 18 which is in engagement with a vertical bearing pin 19 formed as an integral part of a bracket 20. This bracket is rigidly secured to the inner side of the door 10 adjacent the top thereof.

Reference being had to Fig. 2, it is seen that the pivotal point 17 of the operating arm 16 is only slightly out of alignment with the hinge pin of the door hinges 21. Therefore, as the arm 16 is swung about 60 the pivotal point 17, its outer end 18 will swing on substantially the same radius as the door. The slight distance between the two pivotal points is provided for by the slot formed in the outer end 18 of the operating arm.

Pivotedly mounted as at 22 on the operating arm, is a latch lever 23 which is connected by rods and a bell crank 25 to a latch control cam 26. This cam, as illustrated 65 in Fig. 3, is pivotally mounted in the wall at the inner side of the door keeper plate 27 and in register with the keeper opening 28 therein. This cam when swung in the direction of the arrow "A" will enter the 70 opening 28 and force the keeper 29 of the door latch from engagement therewith.

The inner end of the operating arm 16 is formed with a recess 30. The portion of the lever forming the inner edge of this recess 75 is formed on an arc struck from the pivotal point 22 of the latch actuating lever 23, forming an arcuate guide surface 31. A pin 32 is secured in the end of the latch lever 23 and extends downwardly into engagement with the guide surface 31. This pin is connected to the end of an operating rod 33.

It is intended that when the operating rod is moved in the direction of the arrow "B," the pin 32 will travel along the guide 80 surface 31 and thus swing the latch lever 23, and thereby actuate the cam 26 to disengage the keeper 29 from the keeper plate 27. When the pin 32 reaches the end of the guide surface 31 and engages the notch 34 85 therein, the operation mentioned will be accomplished and continued movement of the operating rod 33 and pin 32 will swing the operating arm 16 and open the door. When 90 closing the door the action is similar, inasmuch as the pin 32 first traverses the length of the guide surface 31 to swing the lever 23 and return the cam 26 to a pos- 100 105

tion unobstructing the opening in the keeper plate. Continued movement of the operating rod and the pin 32 will then swing the arm 16 to close the door.

As shown in Fig. 2 a spring 34 acts against the pin 32 and constantly tends to force the latch lever 23 to a position maintaining the cam 26 in an unobstructing position. This, when the door is open, permits the door to be closed, when desired, without the necessity of actuating the mechanism.

Devices of the character forming the subject matter of this application are usually employed in dwellings of two or more stories for the convenience of the tenants in the upper stories and to permit them to open or close the entrance door of the building without having to go to the door and open or close it in the usual manner. The operating mechanism is usually located at the top of the stairs leading to the door. In the accompanying drawings this point is indicated at 35.

The operating mechanism comprises a pivotal lever 36 mounted on the exterior of the wall and connected with a crank arm 37 mounted in the wall. This arm is connected by a rod 38 to one leg of a pivotal bell crank 39. The other leg of the bell crank is connected to the operating rod 33. It is seen that by the use of bell crank levers, the operating lever 36 may be mounted at any desirable point.

In operation, the device is assembled and mounted in the walls before the interior finish is completed. Therefore, when the wall is completed the entire mechanism is concealed with the exception of the operating lever and the end of the operating arm. This arm projects and swings through a small opening formed in the wall near the top of the door casing as indicated at 40 in Fig. 1.

From the foregoing it is clear that movement of the operating lever in one direction unlatches the door and then swings it open. When the lever is returned to normal position the door is closed and permitted to latch.

As mechanism of this character is practically sealed up in the wall, it is very desirable that it be positive in operation and not liable to become inoperative from breakage or any other disorder necessitating repairs or adjustments.

From the foregoing it is obvious that a very simple door opening and closing mechanism is provided which is positive and efficient in operation, and comparatively easy to manipulate.

While I have shown the preferred form of my invention, it is understood that various changes in the construction of the de-

vice may be made without departing from the invention as defined by the appended claims.

Having thus described my invention, what I claim and desire to secure by Letters Patent is:—

1. In combination with a wall having a door frame, a door hinged therein, a door manipulator for swinging said door open and closed, said manipulator comprising an arcuate arm arranged in a horizontal plane above the door and pivoted within the wall in substantial alignment with the hinging point of the door, one end of said arm projecting outwardly through the wall and being formed with a slot, a bearing pin fixed to the door and extending through said slotted end of the arm, a reciprocable operating rod mounted in the wall and adapted to be operated to swing the arcuate arm about its pivot point to open and close said door.

2. In combination with a wall having a door frame, a door hinged therein, a door manipulator for swinging said door open and closed, said manipulator comprising an arcuate arm disposed in a horizontal plane and pivoted within the wall above the door, the pivot point of said arm being in substantial alignment with the hinging point of the door, one end of said arm projecting through said wall and being formed with a slot, a bearing pin fixed to the door and extending vertically through said slot whereby swinging movement of the arm will be accompanied by swinging movement of the door, a latch mechanism on the door, a pivoted cam mounted adjacent the keeper in the latch mechanism in register with the keeper opening therein and adapted when actuated to enter said opening and disengage the keeper therefrom, a latch lever pivoted to the arcuate arm and having one end operatively connected to said cam, a pin secured on the other end of the latch lever, a guideway formed on said arcuate arm having abutments at its ends, said pin being adapted to travel along said guideway and engage said abutments, spring means tending to maintain said pin at one end of said guideway whereby to hold said latch lever in position rendering said cam inoperative, a reciprocable rod mounted in the wall and connected to said lever, initial movement of said rod causing swinging movement of said latch lever to operate the cam until said pin on said latch lever has engaged the abutment at the other end of the guideway and further movement of said arm swinging said arcuate lever to open the door.

ERNEST SCHMITZ.
